UNITED STATES PATENT OFFICE.

JOHN J. JONES, OF BRAMAN, OKLAHOMA TERRITORY.

CHURN.

SPECIFICATION forming part of Letters Patent No. 641,116, dated January 9, 1900.

Application filed September 19, 1899. Serial No. 730,975 (No model.)

To all whom it may concern:

Be it known that I, JOHN J. JONES, residing at Braman, in the county of Kay and Territory of Oklahoma, have made certain new 5 and useful Improvements in Churns, of which the following is a specification.

My invention is an improvement in the class of working-body churning.

I support the cream receptacle or body of 10 my churn in a light frame hung from a crank-shaft, which, being rotated, imparts a reciprocatory and oscillatory movement to said body, and thus quickly separates the butter from the other constituents of the cream.

15 The construction, arrangement, and operation of parts are as hereinafter described, reference being had to accompanying drawings, in which—

Figure 1 is a perspective view of my improved churn. Fig. 2 is a perspective view of the supporting frame or hanger for the churn-body. Fig. 3 is an enlarged vertical section of the upper end of the churn-body and the metal frame or "spider" employed 25 for securing the cover thereon. Fig. 4 is a plan view of the supplemental base-support for the churn-body.

I employ a suitably-braced wooden frame for supporting the churn proper. A crank-shaft 1 is arranged horizontally in suitable 30 bearings on the top bars *a* of said frame and provided with a balance or fly wheel 2 at one end and a pinion 3 at the other. A gear 4, mounted on a stub-shaft, meshes with the 35 pinion 3 and is rotated by a hand-crank. It is obvious that upon turning the latter the crank-shaft 1 will be rotated at a multiplied rate.

The metal frame or hanger 6 for supporting the churn-body or cream-receptacle 7 is hung from the crank-shaft 1, and therefore reciprocates and oscillates as the latter rotates. The side bars of said frame or hanger 6 are provided with hooks, by which it is 45 suspended from the crank proper of shaft 1. These hooks are rigidly connected and braced and secured to the crank by means of a thick wooden bar *6^a*, (see Fig. 1,) to which they are bolted. The lower ends of the 50 hanger-arms are bent laterally (see Fig. 2) and joined by a straight bar. A similar stirrup-like piece *6^b* is pivoted to the main por-

tion 6 of the hanger at the angles of its vertical arms. These stirrups furnish the base-support of the churn-body 7, but I preferably employ a supplemental base 8, Fig. 4, which is arranged intermediately of the churn-body and hanger-stirrups *6^b*. It is a circular plate or disk constructed of any thin light material and provided with two sets 60 of forked lugs 9 and 10, between which the hanger-stirrups *6^b* are held, as will be readily understood.

The upper end of the churn-body 7 is held in place in the hanger 6 and its cover 11 is 65 secured tightly in place by one and the same means—namely, the conical skeleton frame or spider 12 and a crank-screw 13. The spider is composed of a circular rim *12^a*, having pendent lugs or flanges *12^b*, and several 70 arms *12^c*, that converge to a central block *12^d*, upon which the point of the screw 13 bears when the spider 12 is set in due position on the churn-body 7, as shown in Figs. 1 and 3. In such case the rim *12^a* of the spider rests upon the outer edge of the cover 11 and its lugs *12^b* fit over the edge, and thus hold said cover tightly in place. The screw 13 works vertically in a threaded bearing (see Fig. 1) attached to the brace-bar *6^a*, and 80 its crank projects above that of the shaft 1, so that it may be freely rotated to secure or release the churn-body 7 as required.

To balance the weight of the crank and the parts suspended from it, I employ the lifting-spring 15, which is attached at its lower end to a cross-bar *b* of the wooden frame *A* and its upper end connected by an S-shaped hook 16 with the crank proper of shaft 1. It is obvious that the spring 15 will be under increased tension when the crank swings down 90 and will to that extent assist in raising the same in the next half of the revolution. As a further counterbalance the fly-wheel 2 is weighted at 17 on the side opposite the crank 95 of shaft 1.

It is apparent that the rotation of the crank-shaft 1 will cause the churn-body 7 to reciprocate endwise and also swing laterally. To limit such lateral movement, I provide a pivoted and jointed stay consisting of a rod 18, Fig. 1, hinged to an adjacent cross-brace *c* of frame *A*, and a bifurcated or V-shaped piece or loop 19, which is attached to the inner end

of said rod and also to the hanger-stirrup, from which it is pendent. This stay will obviously follow the movements of the churn-body 7 without permitting other than a slight lateral play of the same. The loop 19 may be constructed of strap-steel, so as to have sufficient elasticity to permit the hanger-stirrups to be brought nearer each other or spread farther apart, according to any variation that 10 may be preferred in the distance between the lugs 9 and 10 of the base 8.

It is apparent that the churn-body with the spider 12 may be quickly set and secured in the hanger 6 upon the base 8 or removed 15 therefrom by adjusting the crank-screw 13, so as to bear upon and clamp or release the spider.

In practice the churn-body is provided with lateral handles for convenience in handling.

What I claim is—

The combination with the supporting-frame and horizontal crank-shaft thereon, of a hanger for the churn-body which is suspended from the crank, a brace-bar arranged below the crank, a screw-nut attached thereto, a 25 screw working vertically therein, and a device which is applicable to the churn-body for clamping it in place, substantially as shown and described.

JOHN J. JONES.
